(57) **CLAIM**

The ornamental design for smart glasses, as shown and described.

DESCRIPTION

FIG. 1 is a top, front, left side perspective view of smart glasses, showing our new design.

FIG. 2 is a left side elevation view thereof.

FIG. 3 is a right side elevation view thereof.

FIG. 4 is a front elevation view thereof.

FIG. 5 is a rear elevation view thereof.

FIG. 6 is a top plan view thereof.

FIG. 7 is a bottom plan view thereof; and,

FIG. 8 is a bottom, rear, right side perspective view thereof. The broken lines in the figures illustrate portions of the smart glasses that forms no part of the claimed design.

1 Claim, 8 Drawing Sheets
